UNITED STATES PATENT OFFICE

2,573,630

SLICING MACHINE WITH GAUGE PLATE
ADJUSTING MEANSAdrianus van Duyn, Hillegersberg, Rotterdam,
Netherlands, assignor to U. S. Slicing Machine
Company, Inc., a corporation of IndianaApplication August 4, 1947, Serial No. 766,025
In Great Britain October 14, 1946

4 Claims. (Cl. 146—102)

1

This invention relates, in general, to slicing machines of the type in which the substance to be sliced is supported upon a carrier that is movable to and fro, past a circular knife that is journaled in a housing, and rotated by driving means enclosed therein, the substance being fed step by step across said carriage to a slice thickness gage, which latter presents a face for the substance to contact in the movement of the carrier, and which slice gage has mechanism for adjusting the slice thickness setting.

In slicing machines of this type, the gage plate is usually supported directly by the base of the housing, and it has been found that a gage plate so supported is subject to bending or deflection by the pressure of the substance thereagainst. Moreover, in prior machines the space behind the gage plate is obstructed by the supporting means for said gage plate, and often by mechanism extending behind and/or below the gage plate for adjustment of the slice thickness setting.

It is one of the objects of the present invention to overcome these difficulties and objections, and to provide improved means whereby the gage plate for governing the slice thickness is supported and guided on the housing enclosing the driving mechanism for the knife, thus leaving the space behind said gage free from obstruction by gage-supporting means.

Another object is to provide improved means for supporting and adjusting the slice thickness gage.

A further object is to provide in a machine of this character, an improved slice thickness gage, and improved means associated therewith for guarding or protecting the lower edge of the slicing knife.

A further object is to provide improved indicating means for indicating the extent of adjustment of the slice thickness gage.

A still further object is to provide a machine of this type, wherein the reciprocable carriage and the substance support are interconnected to form a rigid structural unit, which takes the force due to the weight of the carrier component and the substance thereon, the reciprocating motion of the support component, and the slicing action of the knife, and which elements are dis-connectible by the act of lifting the carrier component.

Still another object is to provide an improved carrier construction which is supported and guided by means disposed and housed within the base of the machine.

2

To the attainment of these ends, and the accomplishment of other new and useful objects as will appear, the invention consists in the features of novelty in substantially the construction, combination and arrangement of the several parts, hereinafter more fully described and claimed, and shown in the accompanying drawings, illustrating this invention, in which

Fig. 1 is a front view, partly in elevation and partly in section, of a machine of this character, embodying this invention.

Fig. 2 is a detail view, partly in elevation and partly in section, of the indicator.

Fig. 3 is a view, partly in elevation, partly broken away, and partly in section, of Fig. 1, looking in the direction of the arrow.

Fig. 4 is a perspective view of the machine, taken from one side thereof.

Fig. 5 is a perspective view taken from the opposite side of the machine.

Fig. 6 is a perspective view of the machine, taken from the same side of the machine as Fig. 4, but at a different angle.

In the present exemplification of the invention, the numeral 10 designates the usual rotary knife, which is driven from a motor 11, in any suitable manner well known in this art, and which motor is enclosed within a housing 12. Mounted at the top of the housing is a knife sharpener, the cover portion 13, only, of which sharpener is shown.

A substance carrier 14 is provided, and preferably embodies two parts, 15, 16. If desired, a supporting bracket 17 may be connected to the part 16, to co-operate with a portion 18 on the part 15. These parts are connected together in such a manner that they may be separated by raising the part 15 from the part 16. The part 16 has an arm or extension 19, which projects into the base 20 of the housing, through a slot in the wall, and engages and moves along a track or rail 21, in the form of a bar or rod. A roller 22 is also connected with the extension 19, and moves along a track 23, also disposed within the base 20, for guiding the carriage in its reciprocating movement. The top 24 of the base 20 may be arched, as at 25, to extend over and protect the roller 22.

A slice thickness gage 26 is provided to determine the thickness of the slices to be cut, and this plate is provided with means for adjusting it with respect to the cutting plane, by mechanism that is arranged within the housing, and is also provided with means outside of the housing and in a convenient position for the operator,

whereby such mechanism can be operated. To that end, the gage plate 26, in the present exemplification of the invention, is supported by three arms or links 27, 28, and 29. The arms or links 27 and 28 are connected to a rod or shaft 30, that is journaled in suitable bearings 31, and which rod or shaft is disposed in an inclined position, parallel with the plane of the rotary knife.

The arm 30 is pivotally connected to the gage plate, preferably by passing between spaced ears or bearings 32, and pivotally secured in position by a bearing pin 33. The arm or link 27 carries a pin 34, having a conical end which engages in a conical bearing 35 of the frame structure 36 for the gage plate 26. The portion 36 of the frame structure in which the conical bearing 35 is provided, is shaped to serve as a guard for the adjacent part of the knife edge, as well as for the arm or link 27.

The arm or link 29 is secured or connected to a pin or shaft 37, journaled in suitable bearings 38, and carries a pin or projection 39, in an extended portion or leg 40 of the gage plate 26. This extended portion 40 of the gage plate projects below the knife, and serves as a guard for guarding the knife at its lower edge.

The gage plate 26 may be adjusted to and from the cutting plane in any suitable manner, but preferably by means of a hand grip 41, of a bar 42, which bar is fixed to a horizontal bar or shaft 43, journaled in suitable bearings in the framework, and also in a housing 44, which housing, at the front, is provided with projections 45, by means of which it may be bolted or secured to the floor of the main frame by suitable fastening devices 46, such as bolts, screws, or the like.

The shaft 43 carries a worm 47, which meshes with a worm wheel 48, carried by the bar or rod 30. At the other end of the shaft 43 is another worm (not shown), which meshes with a worm wheel 49, carried by the pin or shaft 37. Thus, when the bar or rod 42 is actuated by the handle 41, the rod or shaft 30 will be rotated through the medium of the intermeshing worm and worm wheel 47, 48. The rotation of the shaft 30 will also rotate the pin or shaft 37, through the medium of the worm gear on the shaft meshing with the worm wheel 49 on the pin or shaft. This will cause the gage plate 26 to be moved towards or away from the cutting plane, according to the direction of movement of the bar or rod 42. If desired, springs 50, 51 may be provided, respectively, on the shaft 30 and pin or shaft 37, to compensate the clearance between the respective worms and worm gears.

The usual knife mask 52 may be provided, and bears, at its lower edge 53, upon the machine base, being held in position by means of pins or projections 54, secured to the base and passing into apertures in the base of the mask. The top side of the mask may be held in position by means of a fastening device, well known in this art.

The mask 52 may be formed, in front, with a step 55, serving as an extension of the usual ledge 56 of the gage plate, so that the under side of the mask forms a guard or enclosure for the extension 40, and also for the links or arms 28, 29.

For indicating the degree of adjustment of the gage plate for determining the slice thickness, there may be provided a member 57, which is preferably constructed of glass, and which may be partly recessed into the housing and partly project therefrom. At the front of this member, there is provided a series of indications, such as

figures 58, for reading the desired adjustment, the remaining portion 59 of the member 57 being frosted. At the other side of this plate or member 57, there is also provided a series of numbers for the customer to read, and they are arranged opposite the frosted portion 59, while at the rear side that part of the scale is frosted exactly opposite the numbers on the front side.

The hand grip is provided with a window or opening 60, and a pointer or indicator 61. An electric lamp 62 is disposed within the housing of the machine, to facilitate reading the indication on the member 57.

The hand grip 41 carries a spring pressed plunger 63, which permits the mechanism to be fixed by friction, at any desired point of adjustment. A handle 64 is provided for reciprocating the carriage and the substance support.

With this improved construction, the gage plate, and the means for supporting and adjusting it, are incorporated in the machine as a unit, and as such is removable from the rest of the machine.

While the preferred form of the invention has been herein shown and described, it is to be understood that various changes may be made in the details of construction, and in the combination and arrangement of the several parts, within the scope of the claims, without departing from the spirit of this invention.

What is claimed as new is:

1. In a slicing machine, a housing, a rotary slicing knife on a turning axis, a slice thickness gauge plate extending outwardly of the edge of said knife on one side of said axis, said knife and plate being disposed in inclined planes, a rock shaft disposed below said plate adjacent one edge thereof and journaled in bearings mounted on said housing, arms on the shaft pivotally connected to said plate, a rock shaft remote from the first said shaft, the last said rock shaft also being journaled in bearings mounted on said housing, an arm on the second said shaft, a leg extending outwardly from said gauge plate substantially parallel to the planes of the knife and gauge plate and beneath the knife to leave the space beneath the gauge plate unobstructed by its adjusting mechanism, a pivotal connection between the last said arm and said leg, said arms engaging said plate at connecting points adjacent the edge of said knife and angularly spaced with respect to said turning axis, an intermediate shaft operatively connected to the first and second recited shafts, and an operating member connected to one of said shafts for rocking all of said shafts to adjust said gauge plate.

2. In a slicing machine, a housing, a rotary slicing knife on a turning axis, a slice thickness gauge plate extending outwardly of the edge of said knife on one side of said axis, said knife and plate being disposed in inclined planes, a rock shaft disposed below said plate adjacent one edge thereof and journaled in bearings mounted on said housing, arms on the shaft pivotally connected to said plate, a rock shaft remote from the first said shaft, the last said rock shaft also being journaled in bearings mounted on said housing, an arm on the second said shaft, a leg extending outwardly from said gauge plate substantially parallel to the planes of the knife and gauge plate and beneath the knife to leave the space beneath the gauge plate unobstructed by its adjusting mechanism, a pivotal connection between the last said arm and said leg, said arms engaging said plate at connecting points adjacent

the edge of said knife and angularly spaced with respect to said turning axis, an intermediate shaft operatively connected to the first and second recited shafts, and an operating member connected to one of said shafts for rocking all of said shafts to adjust said gauge plate, the connection between said shafts embodying gear elements.

3. In a slicing machine, a housing, a rotary slicing knife on a turning axis, a slice thickness gauge plate extending outwardly of the edge of said knife on one side of said axis, said knife and plate being disposed in inclined planes, a rock shaft disposed below said plate adjacent one edge thereof and journaled in bearings mounted on said housing, arms on the shaft pivotally connected to said plate, a rock shaft remote from the first said shaft, the last said rock shaft also being journaled in bearings mounted on said housing, an arm on the second said shaft, a leg extending outwardly from said gauge plate substantially parallel to the planes of the knife and gauge plate and beneath the knife to leave the space beneath the gauge plate unobstructed by its adjusting mechanism, a pivotal connection between the last said arm and said leg, said arms engaging said plate at connecting points adjacent the edge of said knife and angularly spaced with respect to said turning axis, an intermediate shaft operatively connected to the first and second recited shafts, said shafts and the connections thereof with said gauge plate being disposed within the machine housing, and means accessible from the outside of said housing for actuating said shafts.

4. In a slicing machine, a housing, a rotary slicing knife on a turning axis, a slice thickness gauge plate extending outwardly of the edge of said knife on one side of said axis, said knife and plate being disposed in inclined planes, a rock shaft disposed below said plate adjacent one edge thereof and journaled in bearings mounted on said housing, arms on the shaft piv-

otally connected to said plate, a rock shaft remote from the first said shaft, the last said rock shaft also being journaled in bearings mounted on said housing, an arm on the second said shaft, a leg extending outwardly from said gauge plate substantially parallel to the planes of the knife and gauge plate and beneath the knife to leave the space beneath the gauge plate unobstructed by its adjusting mechanism, a pivotal connection between the last said arm and said leg, said arms engaging said plate at connecting points adjacent the edge of said knife and angularly spaced with respect to said turning axis, an intermediate shaft operatively connected to the first and second recited shafts, an operating member connected to one of said shafts for rocking all of the shafts to adjust said plate, the connections between said shafts embodying worm gears, and resilient means individual to certain of said shafts to compensate the clearance between the worm and worm wheels.
